UNITED STATES PATENT OFFICE.

CHARLES CARROLL GILMAN, OF ELDORA, IOWA.

FILTERING CISTERNS OR VATS.

SPECIFICATION forming part of Letters Patent No. 341,649, dated May 11, 1886.

Application filed December 11, 1884. Serial No. 150,128. (No model.)

To all whom it may concern:

Be it known that I, CHARLES CARROLL GILMAN, of Eldora, in the county of Hardin and State of Iowa, and a citizen of the United States of America, have invented new and useful Improvements in Filtering Cisterns or Vats, of which the following is a specification, reference being had to the accompanying drawings, forming part of the same, in which—

Figure 1 is a vertical section of a filtering-cistern and a reservoir containing my invention. Fig. 2 is a plan view of several contiguous filtering-cisterns located at the margin of a stream of water, with conduits leading from the stream to the cisterns, together with a common reservoir, into which all the cisterns empty. Fig. 3 is a sectional view of the same, and Fig. 4 is a front elevation of the cistern.

This invention relates to cisterns or vats for filtering liquids, the same being specially adapted to the filtering of water on a large scale for the use of cities or villages; and it consists in cisterns or vats having the peculiar construction and formed of the material herein described and claimed.

My filtering-cistern is constructed as follows: The walls and bottom I make of brick or stone laid in cement, so as to be water-tight. The top may be open. I then lay upon the bottom a number of joists, which are preferably about three by six inches in cross-section, laid on their edges and extending across the cistern. These joists or supports may be of wood, but preferably, for durability and cleanliness, they are of brick or terra-cotta. Upon these supports I lay a false bottom formed of porous terra-cotta slabs from two to three inches in thickness, and extending between and resting upon the supports, the abutting edges being cemented together, so as to form water-tight joints. A false bottom supported in any other way may be used, but the manner described will be found to be preferable. The porous terra-cotta used for this purpose is produced by mixing sawdust with the clay of which the terra-cotta is made, which in the firing is burned out, leaving the terra-cotta porous, as described in United States Reissued Letters Patent Nos. 10,419 and 10,420, granted to me December 11, 1883.

One of the side walls of the cistern is pierced with openings on a level with the bottom and

below the said false bottom between the several joists or supports, for the escape of the water after filtration.

55

My storing vat or reservoir, adapted to receive the water as it escapes from the filtering-cistern, is a simple water-tight inclosure of suitable size to hold the quantity of water which it is desired to store. Its walls are 60 preferably formed of brick or stone cemented together. It is located relatively to the cistern so that its top is on a level with the bottom of the cistern, or nearly so, in order that the water as it issues from the cistern may flow 65 naturally into and fill the reservoir.

In the drawings, A represents the filtering-cistern.

C represents the joists or supports laid on the bottom A' of the cistern, and D the false 70 porous terra-cotta bottom resting on the said supports.

E represents the storing vat or reservoir, placed in the proper position relatively to the cistern, and b the openings in the front wall of 75 the cistern, through which the water escapes from the cistern into the reservoir E.

For the purpose of rendering the process of filtering more perfect, I spread upon the described false bottom D a layer of coarse clean 80 gravel, preferably about six inches thick, and upon the gravel I spread an equal layer of pure sand. The water in percolating through the false bottom alone will usually leave its impurities wholly or in great measure in the porous terra-cotta; but the gravel and sand will greatly aid the filtering process. The said false bottom of porous terra-cotta, in this connection, performs two functions, namely: It acts as an indestructible support for the loose 85 filtering material placed thereon, and also acts as a filter to filter the water passing therethrough after having passed through the sand and gravel.

When the filtering material has become unduly loaded with impurities, the sand and gravel (if they are employed) may be removed and a new supply laid in.

To cleanse the false bottom itself, it is only necessary to take up and turn over the blocks 100 of terra-cotta, when the water, in percolating through them, will force the deposited impurities out the way they entered.

The described cistern, together with its ad-

jacent storage-reservoir, may be located by the margin of a stream from which the supply for a city or town is obtained, and the water from the stream led directly into the cistern through a suitable conduit. In such case the cistern is sunk in the ground to below the level of the surface of the stream and the reservoir sunk to a still lower level.

It is preferable to construct several separate or adjoining filtering-cisterns, which may all discharge into one and the same storage-reservoir. Fig. 2 represents such an arrangement. A A A represent these cisterns located by the margin of a stream, G, the same being sunk in the ground H below the surface of the stream. E is the reservoir, also sunk in the ground, with its top about on a level with the bottom of the cistern. a a a are conduits leading from the stream to the cisterns, and b b b conduits leading from the cisterns to the reservoir. By suitable gates (not shown) connected with these conduits the water may be shut off from either cistern at pleasure, so that one or more of the cisterns may be cleansed, while the other or others may be kept in operation.

When the source of the water-supply will permit it, or where artificial means are employed to raise the water into the filtering-cistern, it is not of course essential that the cistern should be sunk in the ground. It may be placed on or above the ground, with the storage-reservoir located relatively to it, as described.

The use of the described filtering-cistern is not of course limited to the filtering of water. It may be employed to filter other liquids, such as oils, sirups, &c.

The cistern, as well as the storage-reservoir which I have described, may be of any desired dimensions adapted to the quantity of liquid it is desired to filter in a given time.

I am aware that it has been proposed to construct a cistern with a false bottom composed of ordinary bricks, through which the water is filtered, as shown in Patent No. 100,323, to B. B. Redfield; but this I do not claim, for the ordinary brick is too dense to permit the rapid filtration of the water therethrough.

I am aware that a bed of sand has been placed upon a sheet of perforated metal or wire-cloth, as described and shown in patent to J. W. Hyatt, No. 273,539, March 6, 1883; also, that loose filtering material has been placed upon a perforated metal plate; but these constructions differ materially from my invention in two respects—first, because I substitute for the iron support a material which cannot rust or decay, and will last a greatly longer time than iron as a support for the loose filtering material; and, second, because my porous terra-cotta support acts to purify the water passing therethrough, retaining much impurity that may not have been eliminated by the superimposed layer of loose filtering material. A perforated iron plate or wire-cloth supporting a loose filtering material performs no filtering functions, since the openings therein are much larger than the interstices between the particles of the loose filtering material. Such a support serves merely to allow the passage of filtered water—i. e., the water filtered by the superimposed filtering material. I do not claim a support which is a strainer or filter in the broadest sense in which those terms can be used, but only in the sense that it can remove the finer impurities. A wire-cloth support by itself cannot eliminate these finer impurities, but serves only to prevent the passage of sticks and other relatively large foreign bodies.

What I claim as my invention, and desire to secure by Letters Patent, is—

1. A filtering cistern or receptacle provided with a false bottom of porous terra-cotta, acting as a filtering means, as described, and with loose filtering material resting on and supported by said bottom, substantially as described.

2. A filtering cistern or receptacle provided with a false bottom of porous terra-cotta, acting as a filtering means, as described, and with layers of gravel and sand supported by said bottom, substantially as described.

CHARLES CARROLL GILMAN.
